HUGH LOGIE ALLAN AND JAMES MOORE, OF BURMAH, BRITISH INDIA, ASSIGNORS TO THE BURMAH OIL COMPANY LIMITED, OF GLASGOW, SCOTLAND, A BRITISH CORPORATION

WAX SWEATING AND CRYSTALLIZING APPARATUS

Application filed February 9, 1928, Serial No. 253,158, and in Great Britain March 26, 1927.

This invention relates to apparatus for the heat-treatment of wax, comprising a closed vessel which is filled with wax or wax mixture to the exclusion of air, means being provided for uniformly heating and cooling the wax throughout the vessel.

Such apparatus is disclosed in the specification of British Letters Patents Nos. 208195 and 243447 and United States Patents Nos. 1504923 and 1654232, and comprises a vessel which is divided into superposed wax compartments by means of substantially horizontal cells through which heating and cooling mediums are circulated.

According to the present invention, the apparatus comprises an upright vessel which is divided by means of transverse plates or partitions into wax compartments which are heated and cooled by the provision, in each wax compartment, of a series of transverse spiral pipe coils of relatively close pitch. Each transverse partition preferably consists of a single thickness of plate below a layer of reticulated or expanded metal and/or wire 25 gauze which supports the superincumbent mass of wax.

Provision may be made for compensating for the contraction of the wax mass during the cooling phase, by the admission to the top of each wax compartment of an additional charge of wax mixture. The admission of such additional charge of wax mixture is hereinafter briefly termed "supercharging."

The aforesaid transverse partitions or plates do not in themselves provide sufficient heating effect to keep the mass in the space between each transverse plate and its superposed wax support in a liquid state until the sweating operation is commenced, but the heat of the wax mixture admitted by supercharging the wax compartments during the cooling phase is sufficient to keep the mass in a liquid state in the aforesaid space beneath each wax support.

Final melting-out of the sweated or finished wax is effected by means of steam jets or open steam pipes situated in the space between the transverse plate and superposed wax support, preferably at the periphery of

the said space, and if desired also by passing steam into each compartment at or near the top thereof.

By resorting to the aforesaid supercharging, the wax support can be placed relatively close to the transverse plate, but when supercharging is not resorted to or when it is found necessary or desirable, the wax support may be spaced sufficiently from the transverse plate to accommodate a pipe coil in the intermediate space, hot water, hot oil or other heating medium being circulated through this pipe coil to effect preliminary melting-out of the space between the transverse plate and superposed wax support preparatory to sweating. Final melting-out of the sweated or finished wax may be effected in this case by the provision of heating pipes provided in the space beneath each wax support.

The invention will now be hereinafter more particularly described with reference to the accompanying drawings whereon:

Fig. 1 is a vertical sectional elevation through an apparatus constructed according to the present invention. In this view only one set of pipe coils is illustrated in full lines, the other sets of pipe coils being denoted by broken lines.

Fig. 2 is a plan view of the apparatus with the cover plate removed.

Fig. 3 is a detail of the vertical sectional elevation, showing one corner of one of the wax compartments.

Fig. 4 is a cross-sectional view through the jet 36 of Fig. 3, showing also the jet in end view.

Fig. 5 is a detail view of the vertical sectional elevation of a section of the central pipe.

Fig. 6 is a view similar to Fig. 3 showing one corner of a wax compartment as constructed when supercharging is not practised and Fig. 7 is a sectional view taken through the space 13 partially shown in Fig. 6.

Referring to the drawings, the numeral 6 designates the outer shell of a preferably cylindrical vessel which is preferably suitably lagged, for example, with cork and cement, and which is divided into superposed

wax compartments 7 by means of transverse plates, diaphragms or partitions 8, which consist of a single thickness of plate having a central aperture 9 (Fig. 5). In each compartment 7 is a series of transverse spiral pipe coils 10, preferably of uniform pitch, through which water, oil, brine or other suitable heating or cooling fluid is circulated.

The transverse plates 8 are preferably slightly dished or conical to form trays, a short distance above which perforated or wire gauze wax supports 11 are supported upon a similarly dished or conical layer of expanded or other perforated metal 12.

When the apparatus is designed for enabling the wax compartments to be supercharged, as in Figs. 1 to 5, the expanded metal 12 may be supported upon small discs 35, preferably of metal. If supercharging is not practised, pipe coils 14 are fitted in the space 13 (see Fig. 6).

It will be seen that the partitions 8 form trays to receive the wax mixture and that the outer shell 6 forms the sides of the wax trays or the compartments 7.

The upper coils of each set of spiral coils 10 may be further apart than the lower coils of each set, but in an apparatus constructed to be supercharged, the coils should preferably be evenly spaced throughout the compartment. In order to melt the wax out of the space 13 below each wax support, steam jet pipes 36 are arranged at the periphery of the said space and are supplied with steam from a steam header 37.

The melting-out of the wax from the compartments may also be achieved by passing steam into the upper part of each compartment, for example, by the provision near the top of each compartment of steam jets or pipes 44 connected to the steam header 37. A central steam pipe 40 extends through each header 37 for freeing the headers of solidified wax, which is run off through drain pipe 41.

The construction above described enables the depth of the wax compartments to be considerably increased, viz., from about 6 inches in the construction shown in patent specification 1654232 to approximately 30 inches, thereby effecting an important constructional economy.

The arrangement of the heating elements in the form of pipe coils spaced closely throughout the mass of wax under treatment leads to improved heat transference, by reducing the lag of time in the heat transfer. In former designs of wax sweating apparatus, as shown, e. g. in Patent No. 1654232, the heat had to travel along fins or other heat conductors to the wax, whereas the hot pipe coils of the present invention are in close contact with the wax. This greater temperature control enables closer cuts to be obtained in the sweating operation, that is to say, enables the range of the melting points

to be reduced so that with waxes of closely associated melting points, as for example, waxes melting at say 120-125°, 125-130° and 130° to 135° C. it is possible to produce a wax more closely approximating a definite melting point.

Furthermore, the supercharging of the apparatus is believed to be novel and enables the apparatus to start sweating with a full charge, whereas in other existing apparatus for this purpose, the charge is minus the amount of contraction during cooling. The still further advantage of supercharging is that the top of a wax cake is at a higher temperature than the rest of the cake and so prevents any film or skin of wax forming on the surface which would prevent drops from the underside of the transverse plates 8, or oil gathered in depressions, from passing freely through the mass during sweating. Moreover, in this apparatus, the wax on the gauze or reticulated support is not chilled or choked, as is often the case when water is used to support the wax, and in this apparatus, whether or not a coil 14 be used below the reticulated support, as hereinafter described with reference to Figs. 6 and 7, the wax in the space 13 is not subjected to cooling, as the coil 14 is only used for heating purposes, and where no coil 14 is fitted, the supercharging of the wax compartment below prevents undue cooling of the wax in the space 13.

One of the improvements effected by supercharging is that no heating or cooling agency is necessary underneath the reticulated wax supports.

We are of course aware that the use of cooling and heating coils in relatively deep open sweating pans has been common practice for a considerable period, and also that the use of open steam pipes below the wax support is well known for the purpose of melting-out the space beneath the wax support.

An additional advantage of the pipe coils 10 is that they form a better support for the wax, especially if the coil is staggered as shown in relation to the coil immediately above and below it. This is important in preventing undue sagging of the wax, thus promoting free drainage of the sweated oil from the wax.

The coils 10 may be of any convenient diameter of pipe, but the radial pitch of the coils should preferably be 2 inches or not more than 4 inches and the vertical interval between the pipe coils should preferably be 2 inches or not more than 4 inches throughout up to the depth of solidified charge, that is, in a supercharged apparatus.

The staggering of the coils 10 also brings each alternate coil close to the shell 6. This arrangement compensates for the heat lost by radiation from the shell 6, and prevents

the sweating process from being delayed in the proximity of the shell 6. The staggering of the coils 10 also provides additional support for the mass and improves the distribution of heat throughout the mass.

5 According to the present construction, the wax feed and discharge pipe is centrally arranged and consists of a pipe 16 continuous throughout the apparatus and provided below each wax support with slots 38, the transverse plate 8 being preferably flared downwards at the centre, or dished below the depth of the slot 38 and there welded to the central pipe 16. Throughout the central pipe 16 is an inner steam pipe 21 for melting out the portion of the solidified charge in the pipe 16 before the sweating operation is commenced.

10 A branch connection 39 is provided at the upper end of the central pipe 16 for charging the wax compartments and a discharge pipe 23 is provided at the lower end of the pipe 16, into which all the wax compartments discharge through the slots 38 during the sweating operation. The discharge pipe 23 has a valved branch 42 which discharges the sweatings and finished wax into a distributing box 43, which distributes the material to the various receivers for the sweatings and different grades of wax.

15 30 At one side of the shell 6 is provided a vertical pipe or header 17 having branch pipes 18 which open into the wax compartments 7 near the top thereof. The header 17 serves for the escape of air from the wax compartments during the filling thereof with wax mixture, and also serves for supercharging, i. e. the admission of oil or wax mixture to the compartments 7 in order to compensate for the contraction of the mass in the compartments 7 during the cooling phase.

20 35 40 The branch pipes 18 may open close up to the underside of each transverse partition 8 by the provision of knee pipes. As soon as sweating is commenced, the wax contained in the header 17 and feed pipe 16 is melted out by passing steam through steam pipes 20 and 21 which extend centrally through the header and feed pipes respectively.

45 50 In the construction shown, the vessel has a dished or conical bottom 22 to prevent accumulation of sludge in the bottom of the vessel.

55 A feature of the present apparatus is that it does not require to be tilted towards one side, as is the case with the apparatus disclosed in patent specifications Nos. 1504923 and 1654232.

60 65 The present invention also avoids the practice, commonly adopted where a perforated wax support is provided above the tray, of filling below the perforated wax support with water prior to charging the tray with wax mixture.

The method of operation of the apparatus is as follows:—

The vessel is first brought to a temperature slightly above melting point of the wax mixture to be treated by circulating hot water, 70 hot oil or other hot liquid through the pipe coils 10. Molten wax mixture is then admitted to the upper end of the vessel through the charging pipe 16. The liquid wax mixture enters the compartments 7 through the slots 38 in the central pipe 16, filling each compartment in turn. The air displaced by the mixture escapes through the branch pipes 18 and header 17, which is opened to atmosphere through a valve-controlled air vent 75 pipe 24 in the cover 25 of the vessel. When the vessel has been filled, the cooling phase is commenced by reducing the temperature of the water or oil circulated through the pipe coils 10. The cooling of the wax mixture causes 80 contraction of the mass in the vessel and the compartments are filled automatically by admitting further liquid wax mixture to the compartments 7 through the branch pipes 18 by closing the vent pipe 24 to atmosphere and 85 opening the header 17 through a valve or cock 26 to an overhead tank, not shown. The compartments are thus fully charged to the exclusion of air and cooling proceeds to the desired temperature. The sweating phase is 90

95 commenced by first passing steam through the steam pipes 20 and 21 in order to clear the header 17 and central pipe 16 of solidified wax. The melted wax in the header 17 is run off through a drain pipe 27. The melted wax 100 in the pipe 16 runs away through the discharge pipe 23 and a distribution box, not shown, to a receiver, not shown. The sweating process is then accomplished by circulating hot water, hot oil or other hot liquid 105 through the pipe coils 10. The sweated wax is finally melted out of the compartments 7 by admitting steam openly to the space 13 through the steam jets 36. During the sweating process, the header 17 is opened to atmosphere 110 through the vent pipe 24. The steam pipe 20 serves to heat any air drawn into the vessel through the header 17 during the sweating phase.

115 The steam jets 36 may be supplied with either water or steam. This is an advantage as it enables any sweatings below the wax support 11 which have not drained away properly during the sweating process to be washed away.

120 Referring now more particularly to Fig. 2, it will be seen that the ends of the pipe coils 10 open into water spaces 28 and 29 formed in a water chest 30 which extends vertically outside the shell 6, the water spaces 28 and 29 being separated by a vertical partition 31 and serving for the admission and outlet of water for circulation through the pipe coils 10.

125 130 Where supercharging is not adopted, the

contraction of the wax during the cooling phase, which may be from 7% to 15% of its volume, renders it unnecessary to have so many coils 10 at the top of each compartment when sweating, and a lesser number of coils 10 is also required for cooling, because it is desirable not to excessively cool the upper surface of the wax cake. As sweating proceeds and the mass sags to the bottom of the compartment, the whole mass takes up the average temperature of the lower coils. In the apparatus illustrated, the pipe coils 10 are all supplied from the water chest 30, so that it is not possible to isolate any particular coil, but provision may be made for this purpose if so desired, in order to isolate the upper coils as sweating proceeds.

When the apparatus is constructed without provision for supercharging, pipe coils 14 are fitted, as shown in Fig. 6, in the space 13 beneath each wax support.

The pipe coils 14 are provided for heating the space 13 between the partition 8 and wax support 11 in order to melt the wax out of this space before the sweating operation commences. Steam jet pipes 15 are also provided in the space 13 to enable final melting-out of the sweated or finished wax to be effected.

As will be seen from Fig. 7, the pipe coil 14 extends at its end through the water chest 30 and its inlet end is connected to a water supply pipe 32. A steam pipe 33 connects with the water pipe 32 in order that steam may be admixed with the water circulated through the coil 14. The steam jet pipes 15 are for convenience arranged between the loops of the coil 14 and supplied with steam from a steam pipe 34.

Claims:

1. Apparatus for the heat-treatment of wax comprising a closed upright vessel, transverse dished or conical partitions extending across said vessel and dividing said vessel into superposed wax compartments, a series of superimposed transverse pipe coils in each compartment, a perforated wax support below each set of coils, a central pipe extending vertically through the vessel for charging each compartment with wax mixture, and means for escape of the air displaced during charging permitting complete charging to the exclusion of air.

2. Apparatus for the heat-treatment of wax as claimed in claim 1, wherein the pipe coils are of spiral construction and uniform radial pitch throughout.

3. Apparatus for the heat-treatment of wax as claimed in claim 1, wherein the superimposed pipe coils are evenly spaced vertically within each wax compartment.

4. Apparatus for the heat-treatment of wax as claimed in claim 1, wherein the coils have a radial pitch of preferably 2 inches but not more than 4 inches and are spaced at

vertical intervals of preferably 2 inches but not more than 4 inches.

5. Apparatus for the heat-treatment of wax as claimed in claim 1, having auxiliary means for supplying wax mixture to fill the compartments.

6. Apparatus for the heat-treatment of wax as claimed in claim 1, having steam or water jets provided around the periphery of the space immediately beneath each wax support.

7. Apparatus for the heat-treatment of wax as claimed in claim 1, in which a heating pipe and steam or water jet pipes are provided in a space between each partition and wax support.

8. Apparatus for the heat-treatment of wax, comprising an outer upright cylindrical shell, dished partitions extending completely across the interior of said shell to form trays the sides of which are formed by said shell, thereby to form enclosed wax compartments, a central charging and discharging pipe extending vertically through the vessel and having apertures opening into the lower part of each wax compartment, a series of pipe coils in each compartment, a perforated wax support in the lower part of each compartment, a cover for said vessel, and an air vent passage in said cover.

9. Apparatus for the heat-treatment of wax as claimed in claim 1, comprising a vertical pipe or header and branch pipes connecting said header to the space at the top of each compartment for supplying wax mixture and for the supply of air to and its escape from said compartments.

10. Apparatus for the heat-treatment of wax as claimed in claim 1, characterized in that the coils of each series are superimposed and staggered in relation to one another to improve heat distribution and afford better support for the wax cake.

11. Apparatus for the heat-treatment of wax as claimed in claim 1, comprising a vertical header, connections from said header to the space at the top of each compartment, and a steam pipe in the header for heating wax mixture therein and for heating air entering the compartments through the header.

12. Apparatus for the heat-treatment of wax as claimed in claim 1, characterized in that the pipe coils open into water spaces in a vertical chest at the side of the vessel.

In testimony whereof we affix our signatures.
